UNITED STATES PATENT OFFICE.

GEORGE W. GOETSCH, OF ELKINS PARK, PENNSYLVANIA, ASSIGNOR TO QUAKER HOSIERY COMPANY, OF PHILADELPHIA, PENNSYLVANIA, A CORPORATION OF PENNSYLVANIA.

DESIGN FOR A STOCKING.

Application filed October 31, 1927. Serial No 23,961. Term of patent 14 years.

To all whom it may concern:

Be it known that I, GEORGE W. GOETSCH, a citizen of the United States, residing at Elkins Park, in the county of Montgomery and State of Pennsylvania, have invented a new, original, and ornamental Design for Stockings, of which the following is a specification, reference being had to the accompanying drawing, forming part thereof.

The figure is a perspective view of a stocking showing my new design.

I claim:

The ornamental design for a stocking, as shown.

GEORGE W. GOETSCH.
